UNITED STATES PATENT OFFICE.

WILLIAM LOUIS BESSOLO, OF SAN DIEGO, CALIFORNIA.

NUT-WRENCH.

1,157,495.

Specification of Letters Patent.

Patented Oct. 19, 1915.

Application filed December 11, 1913, Serial No. 805,958. Renewed July 7, 1915. Serial No. 38,511.

To all whom it may concern:

Be it known that I, WILLIAM L. BESSOLO, a citizen of the United States, and a resident of San Diego, in the county of San Diego and State of California, have invented 5 an Improvement in Nut-Wrenches, of which the following is a specification.

My invention is an improvement in that 10 type of nut-wrenches in which both jaws are adapted to move toward and from each other to adapt them for gripping and releasing a nut or other object, and in which the jaws are moved toward each other when a pull is applied to the lever handle.

15 I have embodied my improvement in two closely related forms which are hereinafter described and illustrated in the accompanying drawing, in which—

Figure 1 is a side or plan view of the preferred form of wrench. Fig. 2 is an edge view of the same. Figs. 3 and 4 are cross sections on the lines 3—3 and 4—4, respectively, of Fig. 1. Fig. 5 is a longitudinal section of a portion of the wrench. Fig. 6 20 is a side or plan view of the modified or second form of wrench.

I will first describe the invention illustrated in Figs. 1—5. A lever handle 1 is pivoted at 2 in the rear end of a U-shaped 25 metal frame or housing 3. The head of said lever handle is provided with two lateral arms 4 and 5 which are respectively connected with the outer jaw 6 and inner jaw 7. The outer jaw 6 has an extended shank 8 30 which is provided with ratchet teeth 9 pointing outward or toward the jaw. The shank 8 is adapted to slide in a slot formed in the lateral arm 4 of the handle 1, and the ratchet teeth engage a rivet or cross-pin 10 passing 35 through the arm 4. A bowed plate spring 11 is arranged between the jaw shank 8 and the handle 1, as shown in Fig. 1, and serves 40 to hold the ratchet normally engaged with the cross-pin 10. It is apparent that by 45 pressing inward upon the ratchet or toward the handle 1, its teeth may be disengaged from the cross-pin, so as to permit outward adjustment of the jaw 6. The inner jaw 7 is pivoted at 12 in the inner end of the housing 3 and projects laterally from the latter. The outer portion of the jaw is connected by 50 a pivoted link 13 with the forwardly and laterally projecting arm 5 of the handle 1.

It is obvious that the outer jaw 6 may be

55 easily and quickly adjusted in either direction for adapting the wrench for application to nuts or other objects differing in size. It is further apparent that when the wrench has been so applied, upon pulling the lever 1 in the direction of the double arrow (Fig. 1), the result will be that the outer jaw 6 will be drawn backward owing to the connection between its ratchet shank and the cross-pin 10 in the arm 4 of the handle. This movement is indicated by dotted lines 60 in Fig. 1.

65 The effect of the retraction of the jaw 6 is to grip the nut or other object more firmly. It will be further seen that by the same movement of the handle 1, the link 13 70 forces the outer end of the inner jaw 7 more firmly against the nut or other object. Thus the jaws are forced toward each other simultaneously and grip the nut more and more firmly as the pressure on the handle 75 is increased. Upon releasing the handle, it may be moved back to the position indicated in Fig. 1, and the jaws thus separate from the nut sufficiently to allow the wrench to be released from it.

80 In the form of the invention shown in Fig. 6, the shank 8^a of the outer jaw 6^a is formed with a screw thread on opposite edges, and a rotary nut 14 is applied thereto, it being arranged in a slot formed in the 85 back of the housing 3^a. It is apparent that by rotating the nut, the jaw 6^a may be advanced or retracted as conditions require; that is to say, to adapt the wrench for gripping a nut or other object or releasing the 90 same. The inner jaw 7^a is not pivoted as in the former case, but adapted to slide in the housing 3^a with which it is operatively connected by means of cross pins 15 that pass through slots 16 in the jaw and serve 95 as guides for the jaw in its outward and retractile movements. The lateral arm 4^a of the handle 1 is adapted to abut the inner end of the housing 3^a, as shown in Fig. 6.

As will be understood by reference to 100 Figs. 2, 3, 4 and 5, the handle 1 is formed of three parts, one of them being the filling piece 17 which is secured by rivets 18 between thin parallel side pieces.

I claim:

105 In a wrench of the type indicated, the combination with a frame, of opposing jaws, one being provided with a ratchet shank

which is slidable in the frame and the other pivoted in the front portion of the frame, a handle pivoted to the rear portion of the frame and having opposed lateral arms, one of which is provided with a cross-pin engaging the shank of the outer jaw, and a link pivotally connecting the opposite arm of

the handle with the pivoted jaw, as described.

WILLIAM LOUIS BESSOLO.
